US0D1049184S

(12) **United States Design Patent** (10) Patent No.: **US D1,049,184 S**
(45) Date of Patent: ** Oct. 29, 2024

(54) **3D PRINTER**

(71) Applicant: **Shenzhen Creality 3D Technology Co., Ltd.**, Shenzhen (CN)
(72) Inventors: **Huilin Liu**, Guangdong (CN); **Jinhu Zhu**, Guangdong (CN); **Yueling Peng**, Guangdong (CN)
(73) Assignee: **Shenzhen Creality 3D Technology Co., Ltd.**, Shenzhen (CN)

(**) Term: **15 Years**

(21) Appl. No.: **35/517,838**

(22) Filed: **Jul. 20, 2022**

(80) **Hague Agreement Data**

Int. Filing Date: **Jul. 20, 2022**
Int. Reg. No.: **DM/222534**
Int. Reg. Date: **Jul. 20, 2022**
Int. Reg. Pub. Date: **Jul. 21, 2023**

(30) **Foreign Application Priority Data**

Jan. 20, 2022 (CN) 202230038496.7
(51) LOC (14) Cl. **15-09**
(52) U.S. Cl.
USPC **D15/122**

(57)

CLAIM

The ornamental design for a 3D printer as shown and described.

DESCRIPTION

- 1.1: Perspective
- 1.2: Perspective
- 1.3: Front
- 1.4: Back
- 1.5: Left
- 1.6: Right
- 1.7: Top
- 1.8: Bottom

The design is used to print 3D models. The broken lines in the drawings depict portions of the 3D printer and form no part of the claimed design.

1 Claim, 8 Drawing Sheets
